UNITED STATES PATENT OFFICE.

MAX LEVIN, OF CHICAGO, ILLINOIS.

DESIGN FOR AN ICE-CREAM-CONE SERVER.

47,001.

Specification for Design.

Patented Feb. 23, 1915.

Application filed January 11, 1915. Serial No. 1,701. Term of patent 7 years.

To all whom it may concern:

Be it known that I, MAX LEVIN, a citizen of the United States, residing at Chicago, in the county of Cook and State of Illinois, have invented a new, original, and ornamental Design for Ice-Cream-Cone Servers, of which the following is a specification, reference being had to the accompanying drawing, forming part thereof.

The figure is a perspective of an ice cream cone server showing my new design.

I claim:

The ornamental design for an ice cream cone server, as shown.

MAX LEVIN.

Witnesses:

MILDRED STUMPF,
KATHARINE GERLACH.
